US00D824417S

(12) **United States Design Patent** (10) **Patent No.:** **US D824,417 S**
Narinedhat (45) **Date of Patent:** **** Jul. 31, 2018**

(54) **DISPLAY SCREEN OR PORTION THEREOF WITH GRAPHICAL USER INTERFACE**

(71) Applicant: **ADP, LLC**, Roseland, NJ (US)

(72) Inventor: **Satyawan Narinedhat**, Hackettstown, NJ (US)

(73) Assignee: **ADP, LLC**, Roseland, NJ (US)

(**) Term: **15 Years**

(21) Appl. No.: **29/584,421**

(22) Filed: **Nov. 14, 2016**

Related U.S. Application Data

(63) Continuation-in-part of application No. 29/500,204, filed on Aug. 22, 2014, now abandoned.

(57) **CLAIM**

The ornamental design for a display screen or portion thereof with graphical user interface, as shown and described.

DESCRIPTION

FIG. 1 is a front view of a display screen with graphical user interface; and,

FIG. 2 is another front view of thereof, but shown with a different broken line disclosure.

The broken lines showing a mobile device illustrate the environment of the article and form no part of the claimed design. The remaining broken lines, showing a portion of a display screen and portions of the graphical user interface, including dots at the left end of the arc in FIGS. 1 and 2, form no part of the claimed design.

1 Claim, 2 Drawing Sheets
